UNITED STATES PATENT OFFICE.

WILLIAM M. FERBER, OF PHILADELPHIA, PENNSYLVANIA, ASSIGNOR TO J. R. BUNTING BEDDING COMPANY, OF PHILADELPHIA, PENNSYLVANIA, A CORPORATION OF PENNSYLVANIA.

COUCH-HAMMOCK.

1,147,385.

Specification of Letters Patent.

Patented July 20, 1915.

Application filed October 29, 1914. Serial No. 869,219.

To all whom it may concern:

Be it known that I, WILLIAM M. FERBER, a citizen of the United States, residing in the city and county of Philadelphia, State 5 of Pennsylvania, have invented a new and useful Couch-Hammock, of which the following is a specification.

My invention relates to a couch hammock and consists in adapting the ends or end 10 walls thereof to ventilate the body of the couch, or direct a plentiful supply of air thereto, and in providing means for preventing such ventilation or supply when so desired.

It consists further of means for strengthening and reinforcing certain portions of said ends or end walls, as will be hereinafter described.

The invention is satisfactorily illustrated 20 in the accompanying drawing, but the important instrumentalities thereof may be varied, and so it is to be understood that the invention is not limited to the specific details shown and described.

Figures 1 and 2 represent perspective views of portions of a couch hammock embodying my invention, a certain member in one figure being in a different position from that in the other figure. Fig. 3 represents 30 a front elevation of another embodiment of my invention. Fig. 4 represents a vertical section of a portion on line α — α Fig. 1. Fig. 5 represents a perspective view of one of the reinforcing battens or bars employed.

Similar numerals of reference indicate corresponding parts in the figures.

Referring to the drawings:—1 designates the couch hammock composed of the bed bottom 2, the ends or end walls 3, and the 40 rails 4, only one of said ends being shown, which members broadly considered are of usual construction, said rails 4 and bottom 2 forming a frame adapted to support a mattress shown in dotted lines, as also well known.

At the top of the end 3 is firmly secured the bar or batten 5 which extends transversely thereon and is adapted to have the suspension cords 6 passed therethrough, said 50 bar or batten being formed of metal or other suitable material which serves to stiffen or brace said end 3 at the top thereof, and form a firm connection of the cords 6 there-

with. In said end 3 is formed an opening 55 therethrough 7 which is adapted to allow air to circulate and supply air to the seating portion of the hammock and so ventilate the same.

In order to prevent articles such as hats, caps, cushions falling through said opening 60 7 and to prevent in a measure the head or arm of the occupant of the hammock from being projected beyond said end 3, I employ as in Fig. 1 the lacing 8 which is reeved through the battens 9 and 10 respectively 65 at the top and bottom walls of said opening 7, said battens being firmly connected with the adjacent portion of the end 3 and serving also to reinforce said walls and accordingly stiffen or brace said ends at relative 70 places, one of said battens throughout its entire length being shown in Fig. 5.

To the lower portion of the end 3 is firmly secured the bar or batten 11 which extends transversely thereon and serves to reinforce 75 said portion of the end 3. It will be noticed that the bars 5 and 11 and the battens 9 and 10 are inclosed in pieces of fabric and so protected from the atmosphere and contact of the occupant of the mattress, said pieces 80 and battens being stitched or otherwise secured to the end 3, which latter is formed of fabric or other pliable material, as well known.

In Fig. 3, I show in lieu of the lacing 8 85 of Fig. 1, lattice or grille work 12 which accomplishes the same object as the former.

In order to close the opening 7 as in cool weather or when it is desired not to have the air blow or circulate through the couch, 90 I employ the flap or curtain 13 which extends from the lower end of the side 3 over the bottom 2, and is stitched or otherwise secured to the covering of the batten 11 from which said flap formed preferably of 95 fabric or other pliable material may be turned up as in Fig. 2 along the end 3 over the opening 7, thus covering the latter as a shield whereby wind or air is cut off at said opening thus guarding the occupant of the 100 couch from drafts of air, or an undesirable supply of the latter through said end 3.

In order to retain the flap in upright position, I employ the cords 14 which are passed through openings 15 in the free end 105 of the flap and passed around the suspen-

sion cords 6 and tied thereto, as shown in Fig. 2, thus sustaining said flap over the opening and closing the latter.

When it is desired to uncover the opening, the flap is disconnected from the cords 6 and is lowered to full extent when it may be folded on the base portion of the hammock beneath the mattress, and so be out of the way, or upon the mattress if so desired.

Having thus described my invention what I claim as new and desire to secure by Letters Patent, is:—

1. A seating frame, an end wall rising therefrom, transversely-extending battens on said wall at the uppermost and lowermost ends thereof, and places intermediate of the latter, a ventilating passage in said end wall bounded by said intermediate battens, a guard of open work connected with said intermediate battens and occupying said passage, the lowermost batten being adapted to secure said end wall to said seating frame, an air shield connected with said lowermost batten adapted to rise therefrom and cover said open guard, and means on said end frame for retaining said shield in upright position on said wall.

2. In a couch hammock, a seating frame, an end wall rising therefrom, transversely-extending parallel battens on said wall at the top, bottom and intermediate places thereof, suspension cords connected with the upper batten, the lower batten being adapt-

ed to connect said wall with said frame, said wall having a ventilating passage therein, a guard of open work for the latter which is connected with the intermediate battens through openings therein, and a curtain for said guard on said wall adapted to be placed over said cover and said passage from the bottom of said wall and to be folded from said bottom on said seating frame.

3. In a couch hammock, a seating frame, an end wall rising therefrom, transversely-extending parallel battens on said wall at the top, bottom and intermediate places thereof, suspension cords connected with the upper batten, the lower batten being adapted to connect said wall with said frame, said wall having a ventilating passage therein, a guard of open work for the latter which is connected with the intermediate battens through openings therein, a curtain for said guard on said wall adapted to be placed over said cover and said passage from the bottom of said wall and to be folded from said bottom on said seating frame, and cords on said curtain adapted to be attached to said suspension cords for holding said curtain in operative position over the ventilating passage.

WILLIAM M. FERBER.
